UNITED STATES PATENT OFFICE

WILLIAM SCHNELL, OF DETROIT, MICHIGAN, ASSIGNOR TO TERNSTEDT MANUFACTURING COMPANY, OF DETROIT, MICHIGAN, A CORPORATION OF MICHIGAN

DESIGN FOR A COMBINED SMOKING AND VANITY CASE FOR AN AUTOMOTIVE VEHICLE

Application filed September 12, 1929. Serial No. 32,731. Term of patent 7 years.

To all whom it may concern:

Be it known that I, WILLIAM SCHNELL, a citizen of the United States, residing at 5571 Clarendon Avenue, Detroit, in the county of Wayne and State of Michigan, have invented a new, original, and ornamental Design for a Combined Smoking and Vanity Case for an Automobile Vehicle, of which the following is a specification, reference being made to the accompanying drawings, forming part thereof,

Fig. 1 is a front elevation of a combined smoking and vanity case for an automotive vehicle showing my new design; and Fig. 2 is a side elevation of the same.

I claim:

The ornamental design for a combined smoking and vanity case for an automotive vehicle substantially as shown.

WILLIAM SCHNELL.
